UNITED STATES PATENT OFFICE.

PAUL H. DOUGLAS, OF CLEVELAND, OHIO, ASSIGNOR TO THE WELLMAN-SEAVER-MORGAN COMPANY, OF CLEVELAND, OHIO, A CORPORATION OF OHIO.

CRANE.

No. 928,640.

Specification of Letters Patent.

Patented July 20, 1909.

Application filed July 2, 1908. Serial No. 441,576.

To all whom it may concern:

Be it known that I, PAUL H. DOUGLAS, a citizen of the United States, residing at Cleveland, in the county of Cuyahoga and State of Ohio, have invented a certain new and useful Improvement in Cranes, of which the following is a full, clear, and exact description, reference being had to the accompanying drawings.

10 My invention relates to cranes and more particularly embraces cranes used in hoisting and carrying ladles, etc.

The object of the invention is to provide a crane in which it will be impossible to over-turn the hoisting trolley should a hoisting cable break, and also to make it impossible for the ladle or other object carried thereby to drop, due to such a breaking of a hoisting cable.

20 My invention comprises the elements which will be hereinafter completely set forth, and generally speaking, comprises the elements and combinations set forth in the claims.

25 Reference should be had to the accompanying drawings in which—

Figure 1 is a side elevation of a crane constructed in accordance with my invention; Fig. 2 is a sectional elevation of the crane; 30 Fig. 3 is a plan view of the main hoisting trolley; Fig. 4 is an enlarged sectional side elevation of the auxiliary trolley; Fig. 5 is a perspective showing the arrangement of the cables as used in connection with the hoisting mechanism upon the crane.

In Fig. 1 is shown a general arrangement of a traveling crane which is adapted to extend across the room or building in which it is to be used, the opposite ends of the crane being 40 mounted upon tracks 1 which are in an elevated position above the floor, and are supported in any suitable manner. The mechanism for propelling the crane bridge along the track comprises a motor 2 which is geared to shafts 3 and 4 that extend longitudinally of the bridge of the crane and are connected at their extreme ends by means of gearing, represented generally at 5 and 6, to the wheels 7 and 8 at the opposite ends of the 45 crane. A main hoisting trolley 9 is mounted upon the upper portion of the bridge and is adapted to travel the entire length of the said bridge, being actuated by a motor 10, which is mounted upon the carriage of the said trolley. This trolley is provided with suitable

hoisting drums and hoisting cables, the arrangement and construction of which will be hereinafter described. The hoisting cables which are operated by the drums upon the main trolley are connected with the opposite 60 ends of a ladle beam 11 which is provided with depending hooks 12,—the said hooks being adapted to engage the trunnions upon a ladle. It will be quite obvious that the hoisting hooks may be used to lift and transport any desired load, and I therefore do not confine myself only to the use of my crane for hoisting and tilting ladles.

65 The auxiliary trolley, represented generally at 13, is adapted to travel between the two main girders of the bridge and in a plane below the main trolley, so that these trolleys may pass each other in their travel backward and forward in the longitudinal direction of the crane. The auxiliary trolley is 70 also provided with hoisting mechanism and is adapted to assist the main trolley in the handling of loads, or it may be used to engage the eye upon the lower part of a ladle to tip the same when it may be desired. A 75 suitable motor 14 is provided upon this auxiliary trolley to propel it backward and forward along its tracks.

The cage 15 is located at one end of the trolley and at one side of the path of travel 85 of the hoisting tackle upon both the main and auxiliary trolleys. The cage is adapted to carry the attendant who is operating the crane and within this cage will be mounted the necessary controllers and switches for 90 operating the various motors which are used in actuating the different parts of the crane.

The frame of the crane comprises two longitudinal beams 16 and 17 which are spaced apart. These beams are connected at their 95 opposite ends to end beams 18, one of which is shown in Fig. 2. It is evident that these beams may assume any structural shape that may be desired, but I prefer to construct the said beams as box girders. The end beams 100 18 are mounted upon trucks 19 and 20, two of such trucks being secured to the beams 18 at each end of the same. These trucks are each mounted upon two wheels which engage with the tracks 1, in the manner shown in 105 Fig. 1 of the drawings.

Upon the upper ends of the girders 16 and 17 are secured tracks 21, one of said tracks being secured upon each girder and extending throughout the entire length of the said 110

girders. Upon these tracks travels the main hoisting trolley 9.

Upon the inner portions of the girders and resting upon the lower flange thereof are secured brackets 22 upon which are mounted tracks 23, which tracks extend nearly the entire length of the girders 16 and 17. Upon these tracks the auxiliary trolley 13 is adapted to travel.

Heretofore it has been the custom to mount the motor and the gearing for the propulsion of the crane at one end of the main girders forming part of the crane. This has resulted in limiting the travel of both the main and auxiliary trolleys and in prohibiting them from traveling the complete length of the tracks upon which they are mounted, because the hoisting mechanism which hangs downwardly from the said trolleys will encounter the motor and propelling mechanism for the crane, and therefore the tackle cannot be carried to a point so near the end of the bridge as is desirable. It is a purpose of my invention to mount the motor and the propelling gearing and cage outside of and away from the girders which form the bridge of the crane, thus allowing the trolleys to travel substantially the entire length of the girders upon which they are mounted, and so allowing the hoisting mechanism to approach nearer the extreme limits of the crane, thus giving the crane a wide range of use. In carrying out this purpose, I provide a girder 24, which is mounted outside of the girder 16 and is secured at its opposite ends to the end girders 18. Secured to this girder is a foot-walk 25. This foot-walk extends the entire length of the bridge. Mounted upon suitable brackets secured to the floor and girder 24 is the operating gearing 5 and 6 which is used to propel the wheels of the trucks along the bridge to drive it along its track. The longitudinal shafts 3 and 4 are also secured to this girder 24 and the motor 2 is mounted at the central portion of the crane and secured to girder 24. The hoisting mechanism from the main trolley will depend between the girders 24 and 16, and also outside the girder 17. The cage 15 is likewise secured to and supported from the girder 24. It is thus apparent that the entire operating mechanism for the bridge as well as the operator's cage is removed from the path of travel of the hoisting tackle, so that the trolleys may be run to the ends of the track upon which they are mounted and the hoisting tackle brought to a point very near the ends of the bridge.

If it be desired to drive all the wheels upon the bridge, a girder similar to girder 24 may be mounted upon the opposite side of the crane and secured in the same manner to the end girders 18 as is the girder 24. It will then be possible to mount upon the girder just mentioned driving mechanism and a

motor similar in all respects to the mechanism just described.

The main hoisting trolley comprises a frame having side girders 27 and 28 and end girders 29 and 30. This frame is supported upon cross girders 31 and 32 extending transversely of the frame upon which are mounted wheels 33 which are adapted to engage the tracks 21 mounted upon the tops of the girders 16 and 17. A motor 10 is mounted upon the girder 27 and is geared with a shaft 34 which in turn is connected with the wheels so as to drive the same along the track when the motor is operated.

Drums 35 and 36 are mounted in suitable journals which are secured upon the girders 27 and 28, the said drums being located near opposite ends of the girder. Upon the ends of the drums are gears 37 and 38 which mesh respectively with gears 39 and 40. These gears are each mounted at one end of shafts 41 and 42, respectively, the said shafts being mounted in bearings which are carried by the girders 27 and 28. At the ends of the shafts 41 and 42 opposite to the gears 39 and 40 are secured gears 43 and 44. The gear 44 is in mesh with the gear 45 which is mounted upon a shaft 46, which shaft by means of gears 47 and 48 is in operative connection with the motor shaft 49. The gear 43 is in mesh with a gear 50 which is secured upon a stub shaft 51, which gear is in mesh with the gear 45. This provides for the rotation of the gear 43 in a direction opposite to the rotation of the gear 44, so that the drums 35 and 36 will be rotated in opposite directions simultaneously.

Sheave pulleys 52, 53, 54 and 55 are secured by means of brackets to the girders 29 and 30, 31 and 32, two of said brackets being represented at 56 and 57 respectively, in Fig. 2. The brackets are so secured that the sheaves will be each mounted at an angle to the axis of its adjacent drum. Two of the sheaves are mounted in proximity to each drum at the outside thereof and the plane of the sheave is inclined with respect to the plane of the axis of the drum. The motor is positioned approximately at the center of the frame and is supported upon suitable cross girders which are secured to the side members 27 and 28.

Upon each drum are wound two cables which are secured at points 58 to the said drums. The free end of the cable 59 extends downwardly outside of the girder 16 and around a sheave 60; thence up around the sheave 55 and around a second sheave 61; thence around a sheave 62, across the trolley to a sheave 63; thence around a sheave 64, around sheave 53, sheave 65 and around the drum 36 to the point 58 where it is secured to the said drum. The cable 66 is secured in all respects similar to the cable 59, with the exception that the sheaves 54 and 52 are engaged in place of the sheaves 55 and 53.

The sheaves 60 and 61 are mounted in a tackle block 67 which assume the shape shown in Fig. 1 and comprise two side plates 68 and 69 which are secured together in any suitable manner. At the upper portion of these side plates the same are secured together by means of a pin 70, upon which pin the hubs of the sheaves 60 and 61 are journaled. The block 67 has a second set of 10 sheaves mounted therein which are journaled upon a pin 72, which set of sheaves are in all respects similar to the sheaves 60 and 61, and are in engagement with the cable 66. At the lower end of the block 67 is a pin 71 upon which one end of the ladle beam is pivotally secured, and from this beam, in a line below the block 67, depends a ladle hook 12.

It will be understood that there is a second tackle block 67' in all respects similar 20 to the block 67 which is mounted so as to depend outside of the girder 17, and is supplied with sheaves which are in engagement with the cables 59 and 66, in a manner similar to the engagement of the cables with the 25 sheaves in the block 67. The block 67' is likewise provided with a pin at its lower portion, similar to the pin 71, upon which is pivotally mounted one end of the ladle beam 11, and from which end depends a ladle hook 12.

It will be apparent from the above 30 description that each cable is fastened at its opposite ends to the drums 35 and 36, and that between such end portions the cables are in engagement with a series of sheaves.

It will also be apparent that upon the 35 driving of the drums by the motor, the said drums will be driven in opposite directions, so that the cables will be wound upon said drums, or unwound from said drums, according to the direction of rotation imparted by the motor. As the cables are wound upon the drums, the blocks 67 and 67' will be elevated and with the blocks the ladle beam 11. The opposite will be true when the cable is 40 unwound from the drums. Were a single cable used to raise and lower each end of the ladle beam and the cable connected with one end of the beam should break, the excessive weight which would be brought to bear upon

the other cable would be sufficient to cause 45 the trolley to tip in the direction of the greatest weight, and so be pulled from the top of the bridge. I have obviated such a happening by using the two independent cables 50 working simultaneously, one end of each cable being fastened to the drums at each end of the trolley, so that in the event of the breaking of one cable, the weight upon the respective drums will be the same as when

both cables are in commission, with the difference that one cable will be sustaining the 55 entire weight of the ladle or other object which is being operated upon. In the event of the breakage of one of the cables, the ladle 60 may be lowered to the floor of the building

and the broken cable repaired. It will be impossible for the trolley to be tipped from its position upon the bridge because the weight will be sustained by both of the drums and even if both cables should break, 70 the ladle or other object sustained by the hooks would be dropped but the trolley would not be tipped because the weight would be released from both drums simultaneously. However, the likelihood of both 75 cables breaking simultaneously is quite remote.

The arrangement of the cables is shown in perspective in Fig. 5, and the direction of travel of the cables is indicated by the arrows. The sheaves with which the cables 80 are in engagement during their travel are indicated diagrammatically.

Wherever I use the term "cable" in the specification and claims, it is intended to include ropes, chains, wire hawsers, or any other element having the function of the cables herein shown.

It will be noted from the construction which I have described above that several 90 important results are secured. In the first instance, due to the mounting of the motor and operating gear for the crane outside of the path of travel of the hoisting mechanism which is mounted upon the main trolley and 95 outside the path of travel of the auxiliary trolley, the said trolleys are capable of operating nearer the ends of the crane than in the ordinary construction where the motor and operating gear for such crane are located in 100 the paths of travel. This construction also allows a foot-walk to be supported by the outside of the auxiliary girder, so that the attendant may easily gain access to any part of the crane. Secondly, by the particular 105 reeving of the ropes with relation to the hoisting drums upon the main hoisting trolley, I secure the result that at all times the weight upon the two drums is equalized, thus insuring against the tipping of the trolley 110 and also against the dropping of the ladle by the trolley. Again, due to the fact that the hoisting tackle upon the main trolley overhangs the exterior portions of the main girders of the crane, a free path between the 115 girders is left along which the auxiliary trolley may move without hindrance, and the main trolley and auxiliary trolley may pass each other in their travel without interference. Furthermore, the construction of the 120 crane is economical in that no separate supports are required for the rails upon which the auxiliary trolley travels, the main girders of the crane carrying this weight.

Having thus described my invention, I 125 claim:

1. In a crane, the combination, with main girders, of a trolley mounted upon said girders, an auxiliary trolley adapted to travel on tracks intermediate of the main girders, an 130

- auxiliary girder outside of the main girders and connected to the end girders of the crane, and gearing supported from said girder by means of which the crane is propelled.
2. In a crane, the combination of a bridge comprising main and end girders, a trolley adapted to travel along said main girders, an auxiliary girder mounted outside the main girders and connected to the end girders, a motor supported by said auxiliary girder, and propelling mechanism for the crane supported by the said auxiliary girder, said propelling mechanism being operated by the motor, whereby the crane may be moved.
3. In a crane, the combination, with main girders, of a main trolley adapted to travel along said girders, an auxiliary trolley adapted to travel on tracks intermediate of the main girders, hoisting mechanism mounted upon each of said trolleys, an auxiliary girder mounted outside the main girders, and propelling mechanism and an operator's cage supported from said auxiliary girder whereby said trolleys may travel substantially the entire length of the main girders.
4. In a crane, the combination, with a bridge comprising main girders and end girders, of a trolley adapted to travel upon the upper portions of said main girders, an auxiliary girder located outside of the main girders and secured at its opposite ends to the end girders upon the crane, operating mechanism for said crane mounted upon the said auxiliary girder, and hoisting mechanism mounted upon the trolley, said hoisting mechanism depending between the main and auxiliary girders.
5. In a crane, the combination, with main girders and end girders, of a trolley adapted to travel along said main girders, an auxiliary girder mounted outside the main girders and connected to the end girders, a footwalk supported by said auxiliary girder and extending throughout the length thereof, propelling mechanism for the said crane supported by the auxiliary girder, and a motor supported by the auxiliary girder, said motor being adapted to actuate the propelling mechanism whereby the crane may be moved.
6. In a hoisting crane, the combination, with a frame, of a trolley adapted to travel along said frame, hoisting drums mounted at the opposite ends of said trolley, and a plurality of cables, an end of each cable being secured to each drum, the said cables depending outside the frame and adapted to support the load to be raised at a point intermediate the ends thereof.
7. In a hoisting crane, the combination, with a frame comprising main girders, of a trolley adapted to travel along said girders, hoisting drums mounted at opposite ends of the trolley, the axes of said drums being par-

allel with the girders, and a plurality of cables, an end of each cable being secured to each drum, said cables overhanging the frame and supporting the load to be raised at points intermediate of the ends thereof. 70

8. A trolley having drums located at opposite ends thereof, sheaves mounted upon the said trolley, and a plurality of independent cables, each cable having an end secured to each of the drums, said cables engaging 75 the sheaves upon the trolley at points intermediate of the ends of the cables.

9. In a crane, the combination of main girders, a trolley adapted to travel along the upper portions of said main girders, a hoisting drum at opposite ends of said trolley, and a plurality of cables, one end of each of said cables being secured to one of said drums and the other end being secured to the other of said drums, said cables engaging the 80 load at points intermediate of the ends thereof, whereby an equal proportion of the load is supported by each of the drums upon the trolley.

10. In a traveling crane, the combination 90 of a bridge comprising main girders, a trolley mounted on said girders and adapted to travel along the same, hoisting mechanism carried by said trolley, an auxiliary girder located outside of one of the main girders, an operator's cage, and propelling mechanism for the crane, said cage and propelling mechanism being supported by said auxiliary girder.

11. In a traveling crane, the combination of 100 a bridge comprising main girders, a trolley mounted on said girders and adapted to travel along the same, hoisting drums mounted upon said trolley, hoisting tackles connected with said drums and depending 105 therefrom outside of the main girders, an operator's cage, and propelling mechanism for said crane, said cage and propelling mechanism being supported from the bridge outside the path of travel of the adjacent hoisting 110 tackle depending from the trolley.

12. In a traveling crane, the combination of a bridge comprising main and end girders, a trolley adapted to travel along said main girders, an auxiliary girder mounted outside 115 of the main girders and supported by said end girders, propelling mechanism supported by said auxiliary girder, and hoisting mechanism mounted upon the said trolley and depending between a main girder and said auxiliary girder.

13. In a traveling crane, the combination of a bridge comprising main girders, a trolley mounted on said girders and having at each end thereof a hoisting drum the axis whereof 125 is substantially parallel with a girder, and a cable having its ends secured to said drums and supporting the load to be raised at points intermediate of the ends thereof.

14. In a traveling crane, the combination, 130

with a trolley, of hoisting drums mounted at opposite ends of said trolley, and a plurality of cables each having its opposite ends connected to said drums and supporting the load to be raised at points intermediate of the ends thereof.

15. In a traveling crane, the combination of a bridge comprising main girders, a trolley mounted on said girders, said trolley having

19 at each end thereof a hoisting drum, each of said drums having its axis substantially parallel with a girder and each of said drums overhanging the outer portion of its subjacent girder, and a pair of cables each having

15 its opposite ends secured to both of said drums and each supporting the load to be raised at points intermediate of the ends thereof and outside of a girder.

20 16. In a traveling crane, the combination of a bridge comprising a pair of main girders, a trolley mounted on said girders, a hoisting drum mounted at each end of said trolley and having its axis substantially parallel with a main girder, a ladle beam, sheaves at each

25 end of said beam, and a pair of cables each having its opposite ends connected with both of said drums and having its intermediate portion rove around the sheaves at each end of said beam.

30 17. In a traveling crane, the combination of a bridge comprising a pair of main girders

and an auxiliary girder located outside of and spaced from one of said main girders, propelling mechanism for said bridge carried by said auxiliary girder, a trolley mounted 35 on said main girders and having at each end thereof a hoisting drum, each of said drums having its axis substantially parallel with the main girder, and a pair of cables each having its opposite ends secured to both of 40 said drums and each supporting the load to be raised at points intermediate the ends thereof, each of said cables having a load-carrying portion extending between the auxiliary girder and the adjacent main girder. 45

18. In a traveling crane, the combination of a bridge comprising main girders, each having a track, a trolley mounted on said tracks, said trolley having at each end thereof a hoisting drum, each of said drums having 50 its axis substantially parallel with a girder, and a pair of cables each having its opposite ends secured to both of said drums and each supporting the load to be raised at points intermediate the ends thereof and outside of a track. 55

In testimony whereof, I hereunto affix my signature in the presence of two witnesses.

PAUL H. DOUGLAS.
